UNITED STATES PATENT OFFICE.

GUSTAV HUBER, OF STUTTGART, GERMANY.

SEWING MACHINE.

Application filed February 19, 1926, Serial No. 89,279, and in Germany December, 1925.

In my application, Ser. No. 405,927, filed on Aug. 25, 1920, I have described a sewing machine for producing in one operation two seams, to wit, a seam for sewing together or uniting two pieces of fabric and a seam for covering said first seam, the latter seam being known as an over-seam. In the machine referred to, two closely positioned needles carried by one needle bar are provided for producing in cooperation with a looper the regular seam, while the over-seam is produced by a third needle, also cooperating with a looper. To permit the over-seam needle to properly stitch through the edges of the united pieces of fabric, the extreme end of the movable part of the curved arm of the machine is shaped to act as a spreader for spreading the united pieces of fabric, while between the needles for uniting the two pieces of fabric and the over-seam needle is provided a trimming device for trimming off the projecting edges of the two pieces of fabric prior to being covered by the over-seam.

The object of my present invention is to simplify the construction and operation of the machine referred to, and to still further increase the elasticity of the finished seam. To this end, there is provided for the production of the regular seam only one needle, instead of the two closely positioned needles used in my earlier machine, and this one needle as well as the over-seam needle are each carried by a separate needle bar, the two needle bars being arranged one behind the other and being operated each by a separate shaft, which shafts are rotated at the ratio of 2:1 so that the needle for making the regular seam produces two stitches, while the over-seam needle makes only one stitch. With each needle cooperates a looper, there being also provided a hook to cooperate with the over-seam needle, and the two needles are so closely positioned relative to each other that it is possible to sew in very short curves which is of considerable importance in the sewing on of sleeves. From the drive-shaft for operating the needle producing the regular seam there is also derived the operation of all the other mechanisms cooperating with said needle, such as the looper, the feed-device and the presser-foot, while the drive-shaft for the over-seam needle is also used for operating all the other elements cooperating with the over-seam needle.

The various novel features of my present invention will be better understood from the following detailed description with reference to the appended drawing illustrating my improved sewing machine, and in which Fig. 1 is a front elevation of my machine, Fig. 2 is a top plan view of the same, Fig. 3 a detail view, drawn to a larger scale, showing the operation of the looper cooperating with the needle producing the regular seam, Fig. 4 a side view of Fig. 3, Fig. 5 a front elevation of the looper and hook cooperating with the over-seam needle, Fig. 6 a plan view of Fig. 5, Fig. 7 a front elevation of the two presser feet cooperating with the over-seam needle, Fig. 8 a plan view of the same, Fig. 9 a top plan view of the feed-mechanism for the over-seam needle, Fig. 10 a partial side-view thereof, Fig. 11 an end-view of the feed mechanism and Fig. 12 a perspective view of the same and of the spreader.

The general construction and operation of my over-seam sewing machine having been fully described in my said application, Ser. No. 405,927, I shall describe of the construction and operation of the present improved machine only those parts constituting the new features.

The two needles, that is to say, the needle for producing the regular seam for uniting two pieces of fabric and the needle for producing the over-seam together with all their cooperating elements, to wit: presser-feet, feed-mechanisms and loopers, are operated by two separate cam-shafts designated in Figs. 1 and 2, as 1 and 2 respectively. These two cam-shafts are so geared together that they are rotated at the ratio of 2:1, that is, the shaft operating the ordinary sewing needle and its cooperating parts is rotated twice as fast as the shaft operating the over-seam needle and its cooperating parts. Because of this ratio, the ordinary sewing needle will make double the amount of stitches as that made by the over-seam needle, and accordingly, the feed-mechanism and the trimming mechanism operated by shaft 2 will make twice as many movements as the feed-mechanism operated by shaft 1. This arrangement enables in the simplest manner the small elasticity of the ordinary

chain-stitch to adapt itself to the much greater elasticity of the overseam stitch produced by the overseam needle.

With the ordinary sewing needle cooperates the looper indicated in Figs. 3 and 4 at 3 and which by means of the pivot 4, inserted in the eccentric 5 causing the required movement of the feed-mechanism for the ordinary sewing needle, the follower 6 and the pivot 7 is rocked to and fro. The looper being journaled at 8 above shaft 2 thereby is given the required advance and lag relative to the needle.

In Figs. 5 and 6 is shown the arrangement of the looper and hook cooperating with the overseam needle, which parts are actuated by means of the crank shown at 9 and the double bearing shown at 10^a at the left-hand of shaft 1, to which is pivotally connected the double lever 10, the left arm of which carries two fulcrums 11 and 16. To the upper fulcrum 11 is pivoted the link 12, whereby a rocking movement is transmitted to the lever 13 carrying the overseam-looper 14. The latter moves so close to the rear wall of the support 15 for the stitching plate for the regular sewing needle that room is left only for the upward and downward movement of the overseam needle indicated at 52 in Fig. 6. The object of this arrangement is to place the overseam needle as close as possible to the regular sewing needle indicated at 53 in Fig. 6 to enable the needles to sew in very short curves which is very important for the sewing on of sleeves. To the lower fulcrum 16 is pivoted a link 17, which transmits its movement to a lever 18 carrying the hook 19. The movements of the looper 14 and hook 19 are so timed, that they receive the required advance and lag relative to the overseam needle.

The presser-foot device for the overseam needle is illustrated in Figs. 7 and 8. The presser-feet 21^a and 21^b are provided on two intersecting double arm levers 21 fulcrumed at 20. The release of the presser-foot from the material is caused by a bolt 22, which is periodically moved along inclined faces 23 provided on the right-hand arms of the said levers 21, thereby causing the latter to rock about their common pivot so as to release the material, which then can be fed forward. An ordinary spring 24 causes the return movement of the levers 21 to their original positions. The bolt 22 referred to is carried by the one arm of a bell-crank lever 25, the other arm of which, by a connecting rod 27 is connected with the arm 26 operating the needle-bar. In this way said arm is utilized for operating the presser-foot device cooperating with the overseam needle.

Fig. 9 shows the feed-mechanism cooperating with the overseam needle which feed mechanism is located in the curved arm

above referred to. On shaft 1 is provided an eccentric 28 which, by means of the connecting rods 29 and 30, causes the rocking lever 31 to rock about its pivot 54 transmitting its movement by connecting rod 32 to the feed-mechanism 33, which thus is moved back and forth. On shaft 1 is provided a second eccentric 34, which by means of the connecting rods 35 and 36 rocks the rocking lever 37 about the pivot 54, which by means of connecting rod 38, bell-crank lever 39 and link 40, pivotally connected with connecting rod 32 above referred to causes the feed mechanism 33 to move laterally from right to left in Fig. 9, so that the feeder 33 when moving backwards is withdrawn from contact with the material.

To regulate the amount of feed, I provide, as shown by Fig. 10, between the connecting rods 29 and 30 a link 41, which is provided with an arcuate slot 43. By varying the position of the fulcrum 42 in this slot 43, I can vary the movement of the rocking lever 31 and thereby the amount of the feed. This change in the amount of feed, however, may only be effected towards the rear, since the feeder 33 at the forward end must always operate at the same place. To this end the slot 43 is placed at an angle of inclination relative to its fulcrum 42.

In the same way, there is provided a similar link 45 between connecting rods 35 and 36, only that in this case the change in the amount of movement is always from left to right.

Finally, to enable the work-piece, as it leaves the feed-mechanism cooperating with the ordinary sewing needle to enter freely between the forward end of the overseam-feeder 33 and the overseam ledge 49, so as to be immediately gripped by the feeder 33 and pressed against the ledge 49, a movable spreader 47 is provided (Fig. 12) in the movable forward portion of the curved arm, which spreader upon the movement of the feeder 33 toward the rear in Fig. 12 is also moved because of the engagement of the feeder 33 with the shoulder 48 provided in a recess of the spreader 47. As the feeder 33 moves toward the front in Fig. 12 toward the work-piece and the ledge 49 prior to the feed, the spreader 47 which is under the control of a light spring 55, follows along, and with its curved front portion lightly bears against the sewed together pieces of fabric so as to act during the feed as a spreader and adjusting member so as to cause the pieces of fabric to be stitched uniformly by the overseam needle on both sides of the uniting seam.

At the extreme forward end of the curved arm is loosely journaled a pointed member 50 (Fig. 12) which is required to cause very thin pieces of fabric, which are clamped in position by the presser-foot 56 for the regu-

first seam, to be separated immediately at the left of the feed-mechanism (not shown) co-operating with the ordinary sewing needle.

To this end, the presser-foot 56 must with its left plate extend above the loosely mounted pointed member 50. And as the feed mechanism during its feeding movement projects with its teeth above the stitching plate thus lifting the work-piece to be sewed, the said pointed member 50 also must share in this upward movement. Without this pointed member 50 the sewing of very thin pieces of goods would be impossible except through manipulation by the operator.

In Fig. 12, 57 designates the stitching plate, 58 the lower trimming knife, whereas at 21^a and 21^b are shown the presser feet cooperating with the overseam needle.

The pieces of fabric to be sewed move in the direction of the arrow shown in Fig. 12 and pass under the presser-foot 56, then over the trimming knife 58 and over the spreader 47 to be gripped by the feeder 33.

At 59 is shown the stitching hole for the sewing needle and at 60 the stitching hole for the overseam needle.

While I have thus fully described the novel features of my improved machine, I do not, of course, limit myself to the construction as shown, but claim as my invention:

1. In a sewing machine, the combination with two simultaneously operating needles, viz, a sewing needle for sewing together two pieces of fabric and an overseam-needle for producing an overseam covering the first seam, of two rotatable shafts, one operating said sewing needle and the other operating said overseam needle, the ratio of rotation of said two shafts being 2:1.

2. In a sewing machine, the combination with two simultaneously operating needles, viz, a needle for sewing together two pieces of fabric and an overseam needle for producing an overseam to cover the first seam and a trimming device interposed between said two needles, of two rotatable shafts being so geared together as to rotate at the ratio of 2:1, the shaft rotating at the higher speed operating said sewing needle and trimming device, and the shaft rotating at the lower speed operating said overseam needle and associated mechanisms.

3. The combination as specified in claim 1, comprising a looper cooperating with said sewing needle, and means operatively connected with the corresponding shaft and being disposed above the same for actuating said looper in proper timed relation to said sewing needle.

4. In a sewing machine, the combination with two simultaneously operating needles, viz, a sewing needle for sewing together two pieces of fabric and an overseam needle for producing an overseam covering

the first seam, of two rotatable shafts rotating at the ratio of 2:1, the shaft rotating at the higher speed operating said sewing needle, a looper and a hook adapted to co-operate with said overseam needle, and an actuating means operated by the shaft rotating at the lower speed for simultaneously actuating said looper and hook, the said construction permitting a close arrangement of said two needles. 75

5. In a sewing machine, the combination with two simultaneously operating needles, viz, a sewing needle for sewing together two pieces of fabric and an overseam needle for producing an overseam covering the first seam, and a needle bar carrying said overseam needle, of two rotatable shafts rotating at the ratio of 2:1, the faster shaft operating said sewing needle and the slower shaft operating said overseam-needle, by means of said needle-bar, two opposed presser-feet adapted to cooperate with said overseam-needle, and a means operatively connected with said needle-bar for actuating said presser-feet so as to periodically open the same during the feed of the pieces of fabric. 85

6. In a sewing machine, the combination with two simultaneously operating needles, viz, a sewing needle for sewing together two pieces of fabric, and an overseam needle for producing an overseam covering the first seam, of two rotatable shafts rotating at the ratio of 2:1, the faster shaft operating said sewing needle and the slower shaft operating said overseam needle, a feed-mechanism adapted to cooperate with said overseam needle, articulated connecting means between said feed-mechanism and said slower shaft for actuating said feed mechanism to feed the goods to be stitched and periodically moving said feed mechanism into and out of operative position. 100

7. The combination as specified in claim 6, in which said actuating means for the feed-mechanism comprise a means for varying the length of feed of the feed-mechanism. The arrangement being such that the feed-mechanism always starts at the same point. 110

8. In a sewing machine, the combination with two simultaneously operating needles, viz, a sewing needle for sewing together two pieces of fabric and an overseam needle for producing an overseam covering the first seam, of two rotatable shafts rotating at the ratio of 2:1, the faster shaft operating said sewing needle, and the slower shaft operating said overseam needle, a curved arm, a feed-mechanism provided at the free end of said arm and adapted to cooperate with said overseam needle, an eccentric on said slower shaft, pivoted connecting links between said eccentric and said feed-mechanism for moving said feed-mechanism to and fro to feed the goods to be stitched, 120 125 130

BEST AVAILABLE COPY

62

1,612,821

a second eccentric on said slower shaft, and pivoted connecting links between said second eccentric and said feed-mechanism for periodically moving the same laterally into 5 and out of operative position.

9. The combination as specified in claim 8, in which the said pivoted connecting links include means for varying both the to and fro as well as the lateral movement of said 10 feed-mechanism, said means comprising slotted arcuate members permitting variations of the pivotal connections.

10. In a sewing machine, the combination with two simultaneously stitching needles, 15 viz, a needle for sewing together two pieces of fabric and a needle for producing an overseam covering the first seam, of two rotatable shafts rotating at different speeds, the faster shaft operating said sewing 20 needle, and the slower shaft operating said overseam needle, a curved arm, a feed-mechanism provided in said curved arm and adapted to cooperate with said overseam 25 needle, means for actuating said feed-mechanism, and a movable spreading member located in advance of said feed-mechanism and adapted to spread the goods to be sewed so as to enable them to pass above and below said arm.

30 11. The combination as specified in claim 10, in which said spreading member is wedge-shaped and provided with an inner recess forming a shoulder adapted to be engaged by said feed-mechanism, the said 35 spreading member thus being moved laterally together with said feed-mechanism.

12. In a sewing machine, the combination with two simultaneously stitching needles, 40 viz, a sewing needle for sewing together two pieces of fabric and an overseam needle for producing an overseam covering the first seam, of two rotatable shafts rotating at different speeds, the faster shaft operating 45 said sewing needle and the slower shaft operating said overseam needle, a curved arm, a feed-mechanism provided in said curved arm and adapted to cooperate with said overseam needle, means for actuating said feed-mechanism, a movable ledge adapted 50 to cooperate with said feed-mechanism for positioning the goods to be stitched, and a spreading member located in advance of said feed-mechanism for spreading the 55 goods to be stitched so as to enable them to pass above and below said curved arm,

said spreading member moving laterally together with said feed-mechanism.

13. In a sewing machine, the combination with two simultaneously operating needles, 60 viz, a sewing needle for sewing together two pieces of fabric and an overseam needle for producing an overseam covering the first seam, of two rotatable shafts driven at different speeds, the faster shaft operating 65 said sewing needle and the slower shaft operating said overseam needle, a presser-foot cooperating with said sewing needle, a curved arm, a feed-mechanism in said curved arm adapted to cooperate with said overseam needle, and a pointed member 70 loosely mounted in the forward free end of said arm and extending under said presser-foot for separating the goods to be sewed.

14. In a sewing machine, the combination with two simultaneously operating needles, 75 viz, a sewing needle for sewing together two pieces of fabric along their edges and an overseam needle for producing an overseam covering the first seam, of two rotatable shafts driven at different speeds, the faster shaft operating 80 said sewing needle and the slower shaft operating said overseam needle, presser-feet adapted to cooperate with said sewing needle and said overseam needle, and a trimming mechanism 85 located between said sewing needle and said overseam needle for trimming off the projecting edges of the sewed together pieces of fabric.

15. In a sewing machine, the combination with two simultaneously operating needles, 90 viz, a sewing needle for sewing together two pieces of fabric along their edges and an overseam needle for producing an overseam covering the first seam, of two rotatable shafts geared together so as to rotate 95 at different speeds, the faster shaft operating said sewing needle and the slower shaft operating said overseam needle, loopers 100 cooperating with said two needles, a feed-mechanism having a to and fro and a lateral movement cooperating with said overseam needle, and a trimming mechanism provided between said sewing needle and said overseam needle for trimming off the 105 projecting edges of the sewed together pieces of fabric prior to the production of the overseam.

In testimony whereof I affix my signature.
GUSTAV HUBER.
